UNITED STATES PATENT OFFICE.

ANNIE BELLE FRANCIS, OF BIRMINGHAM, ALABAMA.

ENVELOP.

1,125,683.

Specification of Letters Patent. Patented Jan. 19, 1915.

Application filed December 31, 1913. Serial No. 809,718.

To all whom it may concern:

Be it known that I, ANNIE BELLE FRANCIS, a citizen of the United States, residing at Birmingham, in the county of Jefferson 5 and State of Alabama, have invented new and useful Improvements in Envelops, of which the following is a specification.

The invention relates to envelopes, and has for an object to provide an envelop of a simple and durable construction which will readily accommodate itself to articles of various sizes for the purpose of conveniently sending the same through the mails or the like.

15 The invention embodies, among other features, the provision of an envelop which consists of a back and front and a flexible securing strip connecting the back and front to provide a receptacle adapted to receive 20 articles, a sealing flap being arranged in a flexible and yielding portion of the strip to close the opening to the receptacle.

In the further disclosure of the invention reference is to be had to the accompanying 25 drawings, constituting a part of this specification, in which similar characters of reference denote corresponding parts in all the views, and in which:

Figure 1 is a front elevation of the envelop, showing the sealing flap in open position; Fig. 2 is a rear elevation of the envelop, the sealing flap being shown in closed position; Fig. 3 is a horizontal sectional view taken on the line 3—3 in Fig. 2; and 35 Fig. 4 is a vertical transverse sectional view taken on the line 4—4 in Fig. 2.

Referring more particularly to the views, I disclose an envelop 10 consisting of a back 11 and a front 12, preferably made of cloth 40 such as linen or the like, the said back and front 11 and 12 being rectangular and of substantially the same size, with the back adapted to lie on the front so that the edges of the back and front will meet. An elastic yieldable securing strip 13 preferably made of a rubber fabric or the like incloses the longitudinal edges of the back and front 11 and 12 and a plurality of adjacent transverse edges of the back and front, with one 45 edge of the securing strip secured by means of glue or the like to the front and the other edge similarly secured to the back. Now it will be apparent that when the back and front 11 and 12 are secured together as mentioned there will be provided a receptacle 50 55 14 into which articles can be readily placed,

the size of the receptacle being adapted to be increased or decreased in accordance with the size of the article placed therein, this being due to the fact that the securing strip 13 is of an elastic or flexible nature.

A transverse securing strip 15 extends transversely across the open end of the receptacle 14 and has an edge thereof projecting beyond an edge of the front 12 to which the securing strip 15 is preferably gummed or otherwise secured. A sealing flap 16 is gummed or otherwise secured to the projecting portion or edge of the securing strip 15, and it will be apparent that when the sealing flap is folded over on the back 11 and gummed or otherwise secured thereto, the securing strip 15, constituting a yielding connecting means between the sealing flap and front 12 will permit of readily sealing 70 75 the receptacle 14 without danger of the sealing flap 16 tearing or becoming disengaged from the front 12. Thus it will be apparent that whereas in the ordinary envelop now generally used only an article of a limited 80 width or size can be placed in the envelop as the front and back would tend to tear apart, due to the fact that the material from which the envelop is manufactured, and which is usually paper, would not stand the 85 strain exerted along the folding lines of the front and back if an article of a large size were placed in the receptacle formed by the body of the envelop, in my device, when an article of a large size is placed in the receptacle formed by the front and back, the front and back will relatively expand or be 90 moved apart, due to the fact that there is a yieldable connection between the front and back, and this is also true of the sealing flap 95 which is yieldingly connected to the front of the envelop and adapted for rigid connection with the back.

Inasmuch as I preferably form the front, back and sealing flap of my envelop of linen 100 or some other fabric I preferably secure an address plate 17 of paper or the like to the front 12 and upon which the address of the party to whom the article is sent is adapted to be inscribed in the usual manner.

Having thus described my invention, I claim:

As a new article of manufacture, an envelop consisting of a front and a back, mated to have their longitudinal edges relatively aligned, with one of the crossed edges of the front and back in alignment, a yield-

able securing strip overlapping the longitudinal edges and the alining cross edges, with the edges of the securing strip secured to the face of the front and back whereby the said securing strip will yieldingly hold the front and back and form therewith a receptacle having an opening at one end, said opening being adjacent to the ends of the securing strip, a transverse yieldable securing strip carried by the front and extending across the other cross edge of the front, with a portion of the transverse securing strip projecting beyond an end of the front, and a sealing flap secured to the

projecting portion of the transverse securing strip and adapted for connection with the back to provide a yielding seal or closure for the receptacle, one edge of said transverse yieldable securing strip overlapping the face of the front and the other edge thereof overlapping the face of the sealing flap. 15

In testimony whereof I affix my signature in presence of two witnesses.

ANNIE BELLE FRANCIS.
